UNITED STATES PATENT OFFICE.

STEPHEN A. MARKER, OF NEWARK, NEW JERSEY.

BUTTON FOR DRIVING-REINS.

SPECIFICATION forming part of Letters Patent No. 293,760, dated February 19, 1884.

Application filed December 15, 1883. (No model.)

To all whom it may concern:

Be it known that I, STEPHEN A. MARKER, a citizen of the United States, residing at Newark, in the county of Essex and State of New Jersey, have invented certain new and useful Improvements in Buttons for Driving-Reins; and do hereby declare that the following is a full, clear, and exact description of the same, reference being had to the annexed drawings, making a part of this specification, and to the letters and figures of reference marked thereon.

Figure 1 of the drawings is a perspective view of my improved button for driving-reins in position for use; Fig. 2, a similar view, showing the button detached from the rein; Fig. 3, a horizontal section of the same; and Fig. 4, a detail view of the bent wire or brace, showing its ends connected.

This invention relates to certain new and useful improvements on my button for driving-reins, patented April 18, 1882, and numbered 256,714; and it consists in providing said button with a slit or opening extending from the transverse slot or rein-opening to the periphery, which admits of the button being connected to or detached from the rein at any point along the length thereof, thus obviating the necessity of having to put this button on said rein at its end and secure the proper adjustment by sliding to or from said end, as is now the case, and which, owing to the fact that the rein from various causes is frequently enlarged or bulged out at one place and another, is often difficult and at times impossible to accomplish with buttons similar to the one described in my former patent.

The invention further consists in embedding or interposing between the sides of the button a bent wire or casting, for the purpose of strengthening and imparting increased rigidity to said button, while at the same time this bent wire or casting, when found desirable, forms a pivot for one end of a tongue which secures the button in place upon the rein, and a bearing for the other or free end of such tongue, so as to prevent it from working, or being jammed down so far in the material composing the button as to render it difficult to raise when desired to connect or disconnect said button and rein.

In the accompanying drawings, making part

of this specification, A represents my improved rein-button, made preferably of rubber, and having the usual transverse slot or opening 55 a, through which passes the rein B.

Extending from the transverse slot or rein-opening a to the periphery of the button is a slit or opening, b, its purpose being to admit of the attaching or detaching of said button to or from the rein at any point along the length thereof, thereby obviating the necessity of putting this button on at the end of a rein and sliding it along the same to secure the proper adjustment, such an operation being 65 not only awkward and tedious, but at times very difficult or impossible to accomplish.

Embedded or interposed between the sides of the button A is a bent wire or brace, C, for the purpose of strengthening and increasing 70 the rigidity of said button; and, if desired, a tongue, c, may be pivotally connected to one portion of this bent wire or brace, so that its free end will have a bearing on another portion thereof, to prevent its working or being 75 jammed down in the material composing the button, so as to render it difficult to raise when found necessary, in connecting or disconnecting the rein and button, said tongue, when connected to the button, forming a device to 80 secure the same to the rein.

To prevent lateral motion of the button at the slit or opening b, I prefer to have the ends of the bent wire or brace C so formed as to engage one another, thus providing a fastening device when the rein is placed in the transverse slot or opening a. Any suitable means 85 may be employed to accomplish this result, either by having one end of the bent wire or brace so fashioned as to form an eye for the reception of the other end, as shown by Fig. 4, or a short tube may be secured to one end to form a socket for the reception of the other, any other means for the same purpose being 90 equally as good, the simplicity and cost of 95 manufacture, as well as the security with which these ends may be held, being the important features of such a fastening device.

To connect or withdraw the rein from the button, it is only necessary to separate the ends of that portion of the button through which the slit is made sufficiently to enable the rein to pass through the slit, after which the slit will automatically close to prevent the rein

from being accidentally disconnected, and thus retain the button thereon.

Having now fully described my invention, what I claim as new, and desire to secure by 5 Letters Patent, is—

1. A driving-rein button having a transverse slot or opening through it for the reception of the rein, and provided with a self-closing slit or opening extending from said 10 transverse slot or rein-opening to the periphery of the button, in combination with a device for securing said button to the rein, substantially as and for the purpose specified.

2. A driving-rein button having interposed 15 or embedded between its sides a bent wire or brace, substantially as and for the purpose described.

3. A driving-rein button having a transverse opening through it for the reception of 20 the rein or strap thereof, a slit extending

from said opening to the periphery of the button, and a tongue suitably connected directly thereto, substantially as and for the purpose set forth.

4. The combination of a driving-rein button having a transverse slot or opening for the reception of the rein, and a slit or opening extending from said transverse slot or rein-opening to the periphery of the button, with a bent wire or brace interposed or embedded 30 between the sides of said button, and a fastening device for securing the rein thereto, substantially as and for the purpose specified.

In testimony that I claim the above I have hereunto subscribed my name in the presence 35 of two witnesses.

STEPHEN A. MARKER.
